CLAIM

The ornamental design for a telephone set, as shown and described.

DESCRIPTION

FIG. 1 is a front, top and right side perspective view of a cradled telephone set, showing our new design;

FIG. 2 is a top and right side perspective view thereof, with the handset removed from the stand;

FIG. 3 is a left side and front perspective view of the telephone set in cradled position;

FIG. 4 is a right side and back perspective view thereof; and,

FIG. 5 is a view similar to FIG. 1 with raised index access flap.

The solid black coloration shown in the figures is intentional to represent actual, effectual contrast coloring of the surfaces so treated in accordance with established office standards.
